BUILDING FOR WASHING AUTOMOBILES

Marvin Adler, 2024 Bagley Ave.,
Los Angeles, Calif. 90034

Filed June 14, 1967, Ser. No. 7,479

Term of patent 7 years

(Cl. D13—1)

FIGURE 1 is a side elevational view of a building for washing automobiles, having an end to end passageway for moving automobiles therealong in a vehicle washing operation, such building externally embodying my new design, the tips of the spout elements being broken off in this figure.

FIGURE 2 is a top plan view of the whole.

FIGURE 3 is a front elevational view of the same, reduced in scale.

FIGURE 4 is a rear elevation view of the same with the tips of the spout elements again broken off, and showing the vehicle entrance of the building.

The emerging automobile shown in broken lines is for illustrative purposes only. The dominant features of my design reside in the portions shown in full lines.

I claim:

The ornamental design for a building for washing automobiles, substantially as shown and described.
